MECHANICAL LEAD PENCIL

Carl C. Harris, Orange, and Burton E. Newton,
Athol, Mass., assignors to The Sencil Co.,
Orange, Mass., a corporation of Massachusetts

Application January 24, 1950, Serial No. 140,248

6 Claims. (Cl. 120—18)

1

This invention relates to improvements in mechanical lead pencils comprising a straight tubular body with a convergingly tapered end and having lead-engaging and propelling and retracting mechanism, mounted axially therein, with means for extending the lead beyond the tapered end of the barrel for use in writing. In many pencils of this type the pressure applied to the extended end of the lead, when the pencil is in use, often forces the lead into the barrel of the pencil so that the tapered end of the pencil alone engages the surface to be marked thereby preventing proper inscription by the lead upon such surface.

One object of the invention is to provide means for preventing such retraction of the lead into the barrel.

A further object of the invention is to provide a pencil of this character with interengageable means respectively on the barrel and the lead-propelling means for preventing the lead from being forced into the barrel of the pencil by pressure applied to the end thereof, but which will also permit disengagement of the interengageable members to enable the lead-propelling means to extend the lead beyond the tapered end of the barrel or to retract it within the barrel.

A further object of the invention is to provide resilient means acting upon the lead-propelling mechanism which will supplement the action of the means for moving the lead to and from extended position.

The term "lead" is used herein generally to include not only the usual bar of graphite composition, but a bar of any suitable form, composition or color capable of producing a visible inscription on a suitable base.

More specifically the invention relates to improvements in thin writing pencils of the type disclosed generally in Reissue Patent No. 20,481 granted August 24, 1937, and to the embodiment therein of propelling mechanism having means to prevent undesirable retraction of the lead into the pencil body by pressure applied to the end of the lead when extended beyond the tapered end portion of the barrel.

These and other objects and features of the invention will more fully appear from the following description and the accompanying drawings and will be particularly pointed out in the claims.

Preferred embodiments of the invention are shown in the accompanying drawings, in which,

Fig. 1 is an enlarged side view of a pencil embodying the invention;

Fig. 2 is a longitudinal sectional view of the pencil shown in Fig. 1 on a still larger scale;

Fig. 3 is a transverse sectional view on line 3—3 Fig. 2;

Fig. 4 is a view of a U-shaped spring for frictionally applying pressure to the rotatable member shown in Fig. 2;

Fig. 5 is a detail top view, and Fig. 6 a side elevation, of the collar for actuating the rotatable member;

Fig. 7 is a detail view of the lead-propelling member shown in Fig. 2;

Fig. 8 is a detail view of the expelling rod shown in Fig. 2;

Fig. 9 is a view corresponding to the lower portion of Fig. 2 with the parts in extreme lead-expelling position.

The invention is embodied in a thin mechanical lead pencil having a body or barrel of generally rectangular form, preferably of about $\frac{1}{2}$ " in width and $\frac{1}{16}$ " in thickness, and of any desirable length, and with the sides 1 and 2 having opposite longitudinally extending semi-circular corrugations 3 and 4 extending approximately from the center of the length of the pencil to the tip thereof, and narrow edges 5 and 6 integral with and uniting the sides of the pencil. The edges of the barrel at one end convergingly merge into the corrugations 3 and 4 and a conoidal tip 7 having a shank 8 is mounted in the tapering end of the barrel and forms a continuation thereof. The tip is provided with a central axial bore 9 forming a guideway for the lead of the pencil and having a cup-shaped upper end 10 which serves to direct the lead into the guideway if it is withdrawn beyond the upper end of the shank 8.

35 A cylindrical sleeve 11 is rotatably mounted in the socket formed by the corrugations 3 and 4 and extends longitudinally axially of the barrel and is provided with a helical slot 12. A cylindrical lead-engaging and propelling member 13 is

40 slidably mounted in the sleeve 11 and is provided with a laterally extending arm 14 which engages the helical slot 12 in the sleeve 11. The lower end of the propelling member 13 is provided with a short slit 15 to enable the walls thereof frictionally to embrace the upper end of the lead so that upon upward movement of the propelling member the lead will be retracted into the barrel of the pencil.

45 An expelling rod 16 is slidably mounted in the cylindrical lead-propelling member 13 and is provided adjacent its upper end with an arm 17 extending into the helical slot 12 of the lead-propelling member. The arms 14 of the lead-propelling member and 17 of this expelling rod

16 project through the helical slot 12 sufficiently to engage the barrel, preferably in the narrow slot formed between adjacent edges of the corrugations 3 and 4, as shown in Fig. 3, and this prevents rotation of these elements.

The sides 1 and 2 of the pencil and the corrugations 3 and 4 thereof are provided intermediate of their length with opposite registering recesses 18 opening through the corrugations. A cylindrical collar 19, is fixedly secured to a cylindrical, longitudinally ribbed, solid portion 20 at the upper end of the sleeve 11 and is of sufficient diameter to fit within the recesses 18 and extends slightly through the openings thereof. The collar 19 desirably is provided with a knurled surface 21 to enable it to be readily grasped to rotate the sleeve 11.

The upper end of this collar 19 is provided with serrations 25 engageable with the adjacent edges of the upper walls of the recesses 18. The collar is sufficiently shorter than the length of the recesses 18 so that when moved downward to seat on the bottom of the recesses the serrations on the collar are released from engagement with the edges of the upper walls of the recesses. Thus the collar may be freely rotated in turn to rotate the helically slotted sleeve and thereby propel or retract the lead as desired. But any pressure applied to the end of the lead in writing, or otherwise, sufficiently to retract the lead slightly will at once press the helically slotted sleeve upward, the serrations will come into engagement with the edges of the recesses, and thus lock the sleeve against rotation and prevent retraction of the lead. This is an important feature because it not infrequently happens in pencils of this type, especially if the parts are slightly loose or worn, that even normal writing pressure will cause the lead to rotate the sleeve and be withdrawn into the tip of the barrel.

The solid ribbed portion 20 of the sleeve is provided with a cylindrical extension 22. A U-shaped spring 23 engages the inner faces of the edges of the barrel and has reversely curved lower ends 24 which frictionally engage the cylindrical portion 22 of the propelling sleeve. This spring functions to secure a permanent constant slight friction on the solid cylindrical section 22 of the rotary sleeve 11 so that the collar 19 will turn the sleeve 11 in either the direction to propel or the direction to retract the lead with a uniform smooth action. This spring also facilitates the assembly of the parts of the pencil because it enables the various parts to be made with a slight looseness of fit and then rapidly and accurately positioned in the barrel with the insertion of the spring from the top over the section 22 holding the parts centered and under the friction described.

The lead-engaging and propelling member 13 is provided with a slot 51 extending from the arm 14 to a closed portion 50 at the upper end. The arm 17 of the expelling member 16 projects through this slot and is provided with a shorter section 52 riding on the slot 51 so that the longitudinal movement of the member 16 within and relatively to the member 13 is limited by the engagement of the upper edge of the arm 17 with the shoulder 50 and the lower edge of the section 52 with the arm 14 and the range of this relative movement corresponds with the pitch of the helical slot in the sleeve 11.

In the operation of the pencil, with the parts substantially as shown in Fig. 2, the lead is inserted through the bore 9 in the tip and forced

inwardly until it enters the slotted end of the lead-propeling member 13 and is grasped thereby. The propeling and retracting of the lead in the use of the pencil then takes place in the usual manner by rotating the collar 19. When the lead is worn out and is to be entirely expelled the parts are moved into substantially the position shown in Fig. 9. In this position the sleeve 11 is rotated preferably until the arm 14 passes out from the helical slot of the sleeve 11 and engages the upper end of the shank 8 of the tip. Slight continued rotation of the sleeve then brings the expelling member 16 down until the section 52 engages the arm 14 and in this position the end of the expelling member 16 is slightly outside of the tip 7 and the lead entirely discharged. On the reverse rotation of the sleeve the expelling member 16 moves upward until it engages the shoulder 50 whereupon the arms 17 and 14 are spaced apart to correspond with the pitch of the helical slot and the parts are ready for the reception of the new lead and for operation in the usual manner.

The hollow upper end of the barrel provides a socket into which a holder 26 for an eraser 27 may be inserted, the holder 26 desirably being provided with a rib 28 adapted to abut against the end of the barrel.

It will be understood that the embodiment of the invention shown and described herein is of an illustrative character, and that various changes in form, construction and arrangement of parts may be made within the spirit and scope of the following claims.

Having thus described the invention, what is claimed as new, and desired to be secured by Letters Patent, is:

1. A thin mechanical lead pencil having a rectangular barrel of rigid material provided with a conoidal tip and narrowly spaced parallel side walls having intermediate of their length registering recesses opening at the sides, a helically slotted sleeve rotatably mounted in and extending longitudinally of said barrel, lead-propelling means slidably mounted in said sleeve held against rotation with respect to the barrel and having means engaging the helical slot in said sleeve, a cylindrical collar fixedly mounted on said sleeve extending into and through the recesses in said barrel, the said collar acting when rotated in one direction to extend the end of the lead beyond the barrel tip to writing position, and normally separated interlocking means on said collar and barrel moved into positive interlocking engagement to lock said sleeve and collar against reverse rotation by pressure applied to the extended end of the lead.

2. A mechanical lead pencil having a hollow barrel provided with a conoidal tip and with registering recesses open at the sides of the barrel intermediate its length, a helically slotted sleeve rotatably mounted in and extending longitudinally of said barrel, a tubular lead-propelling and gripping means slidably mounted in said sleeve held against rotation with respect to the barrel and having means engaging the helical slot in said sleeve, a cylindrical collar of less length than that of said recesses fixedly mounted on said sleeve with its periphery extending through the recesses, the said collar acting when rotated in one direction to extend the end of the lead beyond the barrel tip to writing position, and normally separated interlocking means on said collar and barrel moved into positive interlocking en-

gagement to lock said sleeve and collar against reverse rotation by pressure applied to the extended end of the lead.

3. A mechanical lead pencil as defined in claim 2, in which the said interengaging means comprises a serrated surface on the upper end of said collar adapted positively to engage an adjacent upper wall of the recesses in said barrel.

4. A mechanical lead pencil as defined in claim 3, in which the serrated upper end of the collar is disengageable by slight longitudinal downward movement from the recess wall to permit reverse rotation of the sleeve to retract the lead.

5. A thin mechanical lead pencil having a conoidal tip and a rectangular hollow barrel of thin rigid material with narrowly spaced side walls provided centrally with complementary longitudinal semi-cylindrical corrugations having intermediate of their length registering rectangular recesses open at the sides, the sides of the barrel convergingly merging from the edges into said corrugations, lead-propelling mechanism comprising a cylindrical helically slotted sleeve rotatably mounted in said corrugations having a solid upper longitudinally ribbed section registering with said recesses and a smooth cylindrical section above said ribbed section, a lead-engaging and propelling member slidably mounted in said sleeve having an arm engaging the helical slot of the sleeve, a knurled collar of slightly shorter length than that of said recesses fixedly secured to the ribbed section of said sleeve and having its periphery extending through the openings of the recesses in said barrel, the said collar acting when rotated in one direction to extend the end of the lead beyond the barrel tip to writing position, serrations in the upper end of the collar act-

ing when undue pressure is applied to the extended end of the lead to engage the upper edge of the adjacent wall or walls of the recesses and thereby prevent reverse rotation of said sleeve and withdrawal of the lead, and a U-shaped spring having its loop mounted in the edges of the barrel and portions of its legs frictionally embracing the smooth cylindrical section of the slotted sleeve acting to maintain said sleeve in proper axial alinement within said barrel and to supplement accurate adjustment of the lead.

6. A thin mechanical lead pencil as defined in claim 5, in which the lead-engaging and propelling member is of tubular form having a slotted lower end to engage the lead and a lead-ejecting rod slidably mounted therein and provided with an arm extending into the helical slot in the sleeve well above the arm of the lead-engaging and propelling member.
